SOAP DISPENSER

Robert E. Sturman, Minneapolis, Minn.

Application June 6, 1958, Serial No. 740,440

4 Claims. (Cl. 222—193)

My invention relates to devices for mixing a treatment material such as soap, detergents or other liquefied materials with a flowing fluid, for example water. For convenience in this disclosure I have shown my invention as a soap dispenser and associated with the water supply to a shower head or nozzle of a shower used for bathing.

It is the primary object of my invention to provide means of a simple, readily installed and conveniently controlled nature whereby a liquid soap or liquefied detergent may be admixed with the water flowing to a shower head, so that the bather need not bother with the ordinary bar or cake soap, a thing which often is a nuisance and sometimes dangerous when a wet and slick piece of soap escapes from the hand. Another object is to provide a soap dispenser operative by suction created by the water flowing through a venturi tube to the shower head, or to a mixing faucet or the like, and which will supply a predetermined volume of the soap at a predetermined rate of admixture and will then automatically shut off to clear the water for rinsing purposes, meanwhile automatically recharging itself ready for the next use.

These and other more detailed and specific objects will be disclosed in the course of the following specification, reference being had to the accompanying drawings, in which—

Fig. 1 is an elevation of the upper portion of the pipe supplying water to a shower head or nozzle, showing the pipe extending upwardly through a wall of the shower and showing my invention as applied for supplying and mixing soap or detergent with the water.

Fig. 2 is an enlarged vertical sectional view, taken along the line 2—2 in Fig. 1 and showing the condition assumed by the parts following the admixture of a measured volume of soap or detergent with the water flowing to the shower head.

Fig. 3 is a view similar to Fig. 2 but showing the parts in the position assumed after the valve has been manually actuated to initiate the admixture of the soap with the water.

Fig. 4 is an enlarged sectional detail view illustrating one manner of connecting a venturi tube into the water supply pipe and showing the suction connection to the throat of the venturi passage.

Referring now more particularly and by reference characters to the drawing, in Fig. 1 A designates a water supply pipe leading upwardly within a wall B for connection as at C to a shower head or nozzle D of any conventional form. In the structure here shown the shower will be located to the right of the wall B and the majority of the components going to make up my invention are shown as applied to and exposed at this same side of the wall. It will be apparent, however that these components may be located at the opposite side of the wall, out of the way of anyone using the shower, and particularly where closet space is available immediately adjacent the shower.

My invention comprises a container or tank 10 of any suitable shape or size, secured as designated at 11 to the wall B at a convenient location well below the shower

head D and provided with a filler opening normally closed by a plug 12 through which the container may be supplied with a liquid soap or detergent and water mixture or any other treatment material which is to be mixed with the water flowing through the pipe A. If desired the top 13 of this container 10 may be provided with an opening (not shown) large enough to accommodate an ordinary cake of soap, if it is desired to use soap and to mix the same with water in the container.

10 At a level above the container 10 the pipe A is provided in any suitable way with a venturi tube or passage 14 through which the water flowing toward the nozzle D must pass and this passage is of conventional configuration to cause the water to first increase in velocity as it 15 enters the tube, resulting in a drop in pressure at the throat and then to restore the water to its normal velocity and normal pressure after it leaves the venturi tube. As seen in Fig. 4 this venturi tube or passage 14 is machined in a T-fitting 15 interposed in pipe A and having a lateral opening 16 from the throat of the venturi communicating with a suction pipe 17 extending outwardly through the wall B above the aforesaid container 10. Said suction pipe 17, outwardly of the wall B, is screwed into a shut-off valve 18 of conventional form and leading from this 20 valve further outwardly from the wall is the lateral branch 19 of an upright tubular valve housing 20. When the valve 18 is opened the suction created at the throat of the venturi 14 will communicate with the interior of the valve housing 20 and as will be presently pointed out 25 the suction thus present in housing 20 will draw off a measured charge of the liquid soap or detergent mixture from the container 10 and mix the same with the water flowing through the pipe A to the shower head D. The shut-off valve 18 may be adjusted to regulate the rate of 30 flow into the venturi 14 or to shut it off entirely as will be understood.

An upright chamber 21 is formed in the container 10 by the provision therein of a cylindrical wall 22 closed at its upper end 23 except for a tapped opening 24 into which the lower end of the aforesaid valve housing 20 is screwed, as is best seen in Figs. 2 and 3. At the lower end the cylindrical element 22 has a closure 25, spaced some distance above the bottom 26 of the container 10 and provided at its center with an opening 27 in which is positioned a foot valve 28 having upper and lower heads 29 and 30 which are larger in diameter than opening 27. The stem portion of the foot valve 28 connecting the valve heads 29—30 is slightly smaller than the opening 27 so that when the upward movement of this valve is unimpeded the pressure of the soap or liquid detergent mixture within the container 10 may slightly unseat the valve and permit this liquid mixture to seep into the chamber 21. A number of radial slits 32 are provided in the lower end of the cylindrical element 22 to enable the contents of the tank 10 to work into the opening 27 and pass the foot valve 28.

Mounted for vertical reciprocation within the chamber 21 is a float 33 having a cylindrical wall 34 slightly smaller in external diameter than the diameter of the chamber 21 itself, so that the liquid contents of the container 10 entering through the opening 27 may work their way between the cylindrical element 22 and the wall 34 into the chamber 21 above the float. This difference in diameter is very slight but any tendency of the float 33 to bind is prevented by the fact that the nature of the liquid content of a container 10 causes it to have a lubricating effect upon the surface of the float and the chamber. The upper and lower ends of the float 33 are closed as shown and contained within the float is a weight 35 which regulates the buoyancy of the float for a purpose presently to appear.

A control valve, designated generally at 36, is pro-

vided in the housing 20 and comprises an elongated valve stem 37 slidable upwardly and downwardly, or axially, with respect to said housing and emerging from the upper end thereof through a packing gland 38 of conventional form. A control knob 39 is secured to the upper end of the valve stem 37 and a valve head 40 is fitted to its lower end. Said valve head 40 is tapered in an upward direction to coat with the lower end of the housing 20 in order to isolate the housing 20 from the chamber 21 in the normal position of the parts or when the valve stem 37 is in its uppermost position, as it is shown in Figs. 1 and 2. Said valve head 40 has a very long taper in order not to bind or wedge itself into place when closed and in addition is provided with a downwardly protruding bumper extension 41 for engagement with the upper end of the float 33, as will also be shortly described.

Normally the float 33 rests at the bottom of chamber 21 in the position of Fig. 3 but the valve head 40 is in its upper closed position of Fig. 2. When the bather then wants to add soap to the water issuing from the shower head D the knob 39 is pressed down to open the valve formed by the valve head 40 as is clearly shown in Fig. 3. Assuming the valve 18 to be open the suction developed in the pipe 17 by the water passing the throat of the venturi 14 will draw the liquid soap from the chamber 21 and the rate of this withdrawal may be controlled by properly adjusting valve 18. As the soap is drawn into the water from the chamber 21 the float 33 will gradually rise in the chamber until the float bumps the valve extension 41 (Fig. 2) and moves the valve head 40 to its closed position again. Thus a measured charge of the soap, or other liquid detergent or material, will be drawn off, i.e., that volume of the soap in chamber 21 above the float 33, and at the same time an equal volume of soap be drawn by suction into the chamber below the float.

Once the float 33 has thus risen and automatically shut off the admixture of the soap with the shower water the float will begin to descend because it is so weighted and because provision is made for the soapy material below to work upward around the float and inside the wall 22 to recharge the chamber 21 above the float when the latter returns to seat in its normal, lowered position of Fig. 3. As the chamber 21 is being recharged the soap from container 10 will flow inward through the slits 32 and then upward past the foot valve 28 which may freely open for this purpose until the float comes to rest against the upper end 27 of this valve again. The atmospheric pressure upon the relatively large body of the liquid soap in the container will ensure the recharging of chamber 21 and to provide an air supply from the ambient air the upper end of wall 22 may be somewhat loosely fitted into the top 13 of container 10 and other suitable means be provided to admit air into the upper part of the container.

In the case of the location of container 10 and associated components on the opposite side of wall B as previously mentioned then, of course, some suitably simple remote control linkage would be extended through the wall to a position convenient for operation from the shower.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A soap dispenser of the character described for use in association with a water pipe leading to a discharge such as a shower head, mixer faucet and the like, comprising in combination, a venturi tube disposed in association with said water pipe to develop suction as the water flows, a tube leading from the venturi tube, a con-

tainer for the liquid soap, a valve having a tubular housing connected to said tube and having an axially movable valve stem, said housing communicating with the container and the container having a hollow enclosed chamber one end of which is connected to the interior of the housing, the other end of the chamber communicating with the interior of the container around said chamber and having a second valve permitting soap to flow from the container upward into the chamber, a valve head on one end of the valve stem normally closing the housing and isolating same from the chamber, a control member on the other end of the stem to unseat the valve head and enable suction developed by said venturi tube to draw the contents of the chamber into the venturi tube for admixture with the water, a float in said chamber rising as the suction withdraws soap from the chamber until the float strikes and reseats said valve head and shuts off further passage of the soap into the venturi tube, and said float being slightly smaller than the interior of the chamber and weighted to descend therein as the chamber is recharged with soap from the container for the next operation.

2. In a soap dispenser of the character described for use in association with a water pipe leading to a shower head, the combination comprising, a venturi tube disposed in association with said water pipe to develop suction as the water flows, a tube leading from the venturi tube, a container for the liquid soap, a valve having an upright tubular housing connected to said tube and having an axially movable valve stem, said housing communicating with the container and the container having an upright hollow enclosed chamber the upper end of which is connected to the interior of the housing, the lower end of the chamber communicating with the interior of the container around said chamber and having a lower end valve permitting soap to flow from the container upward into the chamber, a valve head on the lower end of the valve stem normally closing off the housing and isolating same from the chamber, a control member on the other end of the stem to unseat the valve head and enable suction developed by said venturi tube to draw the contents of the chamber into the venturi tube for admixture with the water, a float in said chamber rising as the suction withdraws soap from the chamber until the float strikes and reseats said valve head and shuts off further passage of the soap toward the venturi tube, and the said float being adapted then to descend in the chamber to recharge the same with soap from the container for the next operation.

3. A soap dispenser of the character described for use in association with a water pipe leading to a discharge such as a shower head, mixer faucet and the like, comprising in combination, a venturi tube disposed in association with said water pipe to develop suction as the water flows, a tube leading from the venturi tube, a manual control valve in said tube for regulating and shutting off flow therethrough, a container for the liquid soap, a second valve having a tubular valve housing connected to said tube and having a vertically movable valve stem, said housing communicating with the container and the container having a hollow enclosed chamber one end of which is connected to the interior of the valve housing, the other end of the chamber communicating with the interior of the container around said chamber and having a foot valve permitting soap to flow from the container upward into the chamber, a valve head on the lower end of the valve stem normally closing the housing and isolating same from the chamber, a control knob member on the upper end of the stem operative to move the valve stem downward to unseat the valve head and enable suction developed by said venturi tube to draw the contents of the chamber into the venturi tube for admixture with the water, a float in said chamber rising as the suction withdraws soap from the chamber

until the float strikes and reseats said valve head and shuts off further passage of the soap into the venturi tube, and the said float being slightly smaller than the interior of the chamber and weighted to descend therein as the chamber is recharged with soap from the container for the next operation.

4. A soap dispenser of the character described for use in association with a water pipe leading to a discharge such as a shower head, mixer faucet and the like, comprising in combination, a venturi tube disposed in association with said water pipe to develop suction as the water flows, a tube leading from the venturi tube, a manual control valve in said tube for regulating and shutting off flow therethrough, a container for the liquid soap, a second valve having a tubular housing connected to said tube and having an axially movable valve stem, said housing communicating with the container and the container having a vertical hollow enclosed chamber the upper end of which is connected to the interior of the housing, the lower end of the chamber communicating with the interior of the container around said chamber, a foot valve in the lower end of the chamber per-

mitting soap to flow from the container upward into the chamber, a float loosely fitted in said chamber past which the soap will flow upward to fill the upper part of the chamber with a measured charge, a valve head on the lower end of the valve stem normally closing the lower end of said housing and isolating same from the chamber, a control member on the other end of the stem to unseat the valve head and enable suction developed by said venturi tube to draw the contents of the chamber above the float into the venturi tube for admixture with the water, said float rising in said chamber as the suction withdraws soap from the chamber until the float strikes and reseats said valve head and shuts off further passage of the soap into the venturi tube, and the said float being weighted to descend therein as the upper end of the chamber is recharged with soap from the container for the next operation.
